FUNNEL OR THE LIKE

John C. Ilg, Fitzwilliam, N.H., assignor to Elliot Laboratories, Inc., Fitzwilliam, N.H., a corporation of New Hampshire

Filed Feb. 17, 1965, Ser. No. 83,840

Term of patent 14 years

(Cl. D44—29)

FIG. 1 is a side elevational view of a funnel showing my new design;

FIG. 2 is a fragmentary elevational view taken from the opposite side;

FIG. 3 is a side elevational view taken from the right of FIG. 1;

FIG. 4 is a top plan view; and

FIG. 5 is a bottom plan view.

The characteristic feature of the design resides in the combination of the tapered neck having a pair of oppositely disposed L-shaped slots in the bottom edge thereof with a flange at the top thereof, of greater diameter than the top of said tapered neck, said top of the tapered neck being of greater diameter than the bottom of the main cone, all as shown.

I claim:

The ornamental design for a funnel or the like, substantially as shown and described.
